SHUTTLE MOTION

Robert J. Bartholomew, Germantown, Pa., assignor to Fletcher Works, Incorporated, Philadelphia, Pa., a corporation of Pennsylvania

Application June 20, 1931, Serial No. 545,746

11 Claims. (Cl. 139—136)

This invention relates to improved shuttle motions, and has for one of its objects the provision of a positive drive for the shuttle rack whereby the objections to the use of flexible drives such as leather straps, woven belting, chains, etc. which are subject to stretch and wear and breakage are overcome. It will be appreciated, furthermore, that with a flexible drive, as distinguished from a positive drive, any stretch in the driving device prevents the shuttle from being thrown home to the end of its stroke, necessitating frequent elimination of the stretch, while breakage of the driving straps or chains causes serious damage to the shuttles as well as to the fabric being woven. These troubles are eliminated in my construction.

Another objection, overcome by the present invention, to the use of straps is that the straps must be adjusted to their maximum tension when the shuttles are at the middle of their stroke, leaving the straps slack at the end of the stroke so that the shuttles are not under proper control. If the shuttles break or do not complete their stroke the fabric being woven is of course damaged.

The present invention also provides a construction which may be applied either between the loom frames or outside the frame just as desired, leaving space where most needed for other mechanisms such as cam motions, head motions, drives, etc.

In the drawings accompanying this application:

Fig. 1 is a side elevational view of an embodiment of my invention;

Fig. 2 is a view taken substantially on the line 2—2 of Fig. 1;

Fig. 3 is a side elevational view of a modified embodiment of the invention; and

Fig. 4 is an elevational view of the apparatus of Fig. 3.

Referring to the embodiment of my invention as illustrated in Figs. 1 and 2. 1 designates a loom batten, 2 and 3 the layswords attached thereto, these layswords being pivoted on a pivot 4 which in the present instance is in the form of a shaft or rod suitably connected in the loom frame. The batten 1 carries shuttle rack 5 for driving the shuttle pinions 6 and shuttles 7. The batten 1 has a rocking motion about the axis of the shaft 4 while the rack 5 as will be understood has a reciprocating motion on the batten.

As above pointed out, one of the objects of my invention is to provide a positive drive for the rack 5, as distinguished from the belt, strap and

chain drives of past structures. To this end, therefore, I provide eccentric gear 8 mounted on drive shaft 9 and meshing with elliptic gear 10. The shaft 9, as will be seen from Fig. 1, is provided with a crank 11 and link L connected at 12 to the batten so as to rock the batten. The shaft 13 carrying the elliptic gear 10 is provided with a mitre gear 14 meshing with a mitre gear 15 on shaft 16.

The shaft 16 is provided with a crank 17 provided with an elongated crank pin 18.

Mounted on supporting rods 19 and 20 which are parallel to the shaft 13 and the ends of which are supported in the layswords 2 and 3 is a reciprocable slotted crosshead 21 receiving the rectangular block 22 which is carried on the crank pin 18 whereby as the shaft 16 is rotated motion will be imparted to the crosshead 21 to effect reciprocation of the same along the supporting rods 19 and 20. The block 22 is elongated as seen from Fig. 1, so as to permit of rocking or pivoting of the crosshead 21 with the batten about the axis of the member 4, without disturbing the driving engagement of the block with the crosshead.

23 designates a driving lever positively connected to the batten rack 5 at 24. This driving lever is pivotally attached by a pivoted member 25 with the batten pivot or rod 4, the lever, as will be seen from Fig. 2 being pivoted to this member to rock about the transverse pivot 26 and also about the longitudinal pivot 4.

A link 27 positively connects the driving lever 23 to the crosshead 21.

The mitre gears 14 and 15 have a one to one ratio and the ratio between the eccentric gear 8 and elliptic gear 10 is such that the crank 17 makes one revolution to two revolutions of the crank 11 which rocks the batten.

It will be seen from the foregoing that I have provided a construction wherein the batten rack 5 is positively driven as distinguished from the leather strap drive, woven belting drive and chain drive heretofore used.

It will be appreciated that by changing the throw of the crank the mechanism can easily be adapted for shuttles of different strokes. When once the apparatus is set it needs no further attention and as most loom fixers are familiar with the elliptic eccentric drive, such as employed in this embodiment of my invention they can easily time this device to give the best results for the particular class of fabric being woven. It will be appreciated, furthermore, that inasmuch as there is no lost motion the speed and position of the

shuttles will be positive and the shuttles will be under complete control at all parts of the stroke.

The embodiment of my invention illustrated in Figs. 3 and 4 is similar in principle to the arrangement just described in that I provide a positive drive for the shuttle rack. Here I employ two eccentric gears 8' and 10' in place of the eccentric and elliptic gears 8 and 10, respectively, of Fig. 1. I have also substituted bevel gears 14' and 15', having a two to one ratio, for the two gears 14 and 15 having a one to one ratio, as in Fig. 1.

The reciprocating block 21' of this figure is supported on the batten pivot 4 by an arm 29 pivotally connected to the reciprocating block at 30. The reciprocating block 21' is provided with an extension 31 connected to the driving lever 23 instead of the arrangement shown in Fig. 2, this extension 31 being rigid with the reciprocating block, as distinguished from the pivoted link 27. As before, the driving lever 23 is positively connected at 24 with the batten rack 5 and is pivoted at its lower end at 26 to the member 25 which is pivoted on the batten pivot 4 so as to swing about the same pivot as the batten 1.

It will be appreciated that in this embodiment of my invention the reciprocating block 21' travels through a small arc as it is reciprocated but the motion of the shuttles 7 is substantially the same as in the embodiment of my invention illustrated in Figs. 1 and 2. Excess rotation of the crosshead is prevented by the single layword 3.

What I claim is:—

1. In combination, a batten, a batten rack, a lever connected to the rack, a slotted pivotally mounted block connected to the lever, a crank for driving the block, an eccentric gear connected to the crank, an eccentric gear for driving the first mentioned eccentric gear, a crank on the shaft of the second mentioned eccentric gear connected to the batten for driving the same, said block crank making one complete revolution to each two revolutions of the batten crank.

2. In combination a pivoted batten, a batten rack carried thereby, a lever for reciprocating said rack, a block pivoting with the batten and connected to said lever to drive the same, a crank rotatable about a fixed axis, a crank pin, and an elongated block carried by said crank pin and engaging said first mentioned block throughout the pivoting of said first mentioned block.

3. In combination, a batten, a pivot for the batten, a batten rack, a lever connected thereto, a crosshead for driving the lever, said crosshead rocking about the same pivot as the batten, and a crank for reciprocating the crosshead.

4. In combination, a horizontal batten including a rack and shuttles, said batten rocking about a horizontal axis, two rods parallel to the batten and rocking therewith, a vertically slotted crosshead carried by said rods, a crank rotating about a fixed axis and carrying an elongated block, said

crank and block reciprocating the crosshead along said rods, a lever secured to the batten rack and pivoting about two mutually perpendicular axes, one of which is the batten axis, and a rigid member connecting the crosshead to the lever. 5

5. In a narrow fabric loom, a pivoted batten rack, a lever connected thereto, a slotted crosshead connected to said lever, a driven crank rotating about a fixed axis and driving said crosshead, a long crank pin and block carried by the crank, said crosshead having a vertical slot for said crank block said crosshead being mounted to move lengthwise of the block as well as lengthwise of the loom. 10

6. In a narrow fabric loom, a batten rack, a lever connected thereto, a slotted crosshead connected to the lever, means supporting the crosshead, and permitting the crosshead to reciprocate lengthwise of the loom and crosswise of the loom at the same time, a crank mounted for rotation only and reciprocating the crosshead lengthwise of the loom, and driving means for the crank. 20

7. In combination, a batten including a rack, a lever connected to the rack, a slotted block, one end of which is connected to the lever and supported thereby, a link supporting the other end of the block, a horizontal rod about which the batten, the lever, the link and the block rock, 30 a crank rotating about a fixed axis, and driving the block, and driving means for the crank. 25

8. In combination a pivoted batten, a batten rack, a pivoted driving lever positively attached to said batten rack, and a block for positively driving said lever, said block pivoting about the same axis as the batten. 35

9. In combination a pivoted batten, a batten rack, a driving lever positively connected to said batten rack, a block for positively driving said lever, said block being mounted to pivot about the same axis as the batten, and to maintain a fixed angular relation to the batten with respect to said axis, and positive means for reciprocating said block. 40

10. In combination a pivoted batten, a batten rack, a driving lever positively connected to said batten rack, a block for positively driving said lever, said block being mounted to pivot about the batten pivot at the same angular velocity as the batten, and a crank rotatable about a fixed axis for reciprocating said block. 45

11. In combination a pivoted batten, a batten rack, a driving lever positively attached to said batten rack, a reciprocable block, a link connecting the block and lever, a support for the block, said batten, driving lever, block, support and link mounted to swing about the batten axis with the same angular velocity, and a crank rotatable about a fixed axis and cooperating with said block to reciprocate the same. 50

ROBERT J. BARTHOLOMEW.
